UNITED STATES PATENT OFFICE.

HATTIE LOUISE HIBBS, OF PRINCEVILLE, ILLINOIS.

SKIRT-MARKER.

1,373,614.

Specification of Letters Patent.

Patented Apr. 5, 1921.

Application filed April 6, 1920. Serial No. 371,697.

To all whom it may concern:

Be it known that I, HATTIE L. HIBBS, a citizen of the United States, residing at Princeville, in the county of Peoria and 5 State of Illinois, have invented new and useful Improvements in Skirt-Markers, of which the following is a specification.

The invention relates to a skirt marker.

The object of the present invention is to 10 provide a simple, practical and efficient skirt marker of strong and durable construction adapted to enable a skirt to be quickly and accurately marked so that the length of the skirt will be uniform at all points.

15 With these and other objects in view the invention consists in the novel construction, combination and arrangement of parts hereinafter fully described, illustrated in the accompanying drawing and pointed out in the 20 claims hereto appended, it being understood that various changes in the form, proportion and minor details of construction, within the scope of the claims, may be resorted to without departing from the spirit or sacrificing any of the advantages of the invention.

In the drawing in which like characters of reference designate corresponding parts in the several figures:

30 Figure 1 is a side elevation of a skirt marker constructed in accordance with this invention.

Fig. 2 is a vertical sectional view of the same partly in elevation.

35 Fig. 3 is a cross section of the hollow arm taken on the line 3—3 of Fig. 2.

Fig. 4 is a plan view of the chalk holder and showing the vertically adjustable rod in cross section.

40 In the accompanying drawing in which is illustrated the preferred embodiment of the invention the skirt marker comprises in its construction a stand 1 preferably in the form of a four-legged stool having centrally 2

45 mounted in it a vertical adjustable screw 2 provided at its upper end with a horizontal attaching plate 3 to which is secured a horizontal platform or support 4. The platform or support is adapted to receive the 50 person being fitted and the screw 2 has mounted on its upper portion a vertical sleeve 5 carrying a horizontal arm 6 preferably rectangular in cross-section and receiving a telescoping rod 7. The sleeve is adapt-

55 ed to rotate on the upper portion of the screw above the threads 8 thereof and the hollow arm is provided at its outer portion with a

set screw 9 for securing the telescoping rod 7 in its adjustment.

The horizontal telescoping rod 7 is provided at its outer end with a vertical sleeve 10 receiving a vertical measuring rod 11 and provided with a set screw 12 for securing the measuring rod in its vertical adjustment. The measuring rod 11 which is provided with suitable graduations is adapted to be raised and lowered to arrange a chalk holder 13 in proper position with relation to the platform or support 4. The chalk holder 13 which is mounted on the upper 65 portion of the measuring rod may be of any desired construction and when the measuring rod is adjusted vertically to arrange the chalk holder in proper position the horizontal hollow arm is adapted to be swung 70 around the upper portion of the screw 2 to enable the skirt to be quickly and accurately marked so that every portion of the skirt will be of uniform length. The adjustment of the telescoping rod and the vertical 75 adjustment of the measuring rod will enable the chalk holder to be adjusted inwardly and outwardly as well as upwardly and downwardly and the chalk is adapted to be arranged at the desired elevation and also 80 the desired distance from the center of the platform. In this manner the chalk may be made to lightly touch and properly mark a skirt or other garment.

What is claimed is:

90 A garment marker including a stool, a rotary platform provided with a depending screw having a threaded lower portion and a smooth upper portion, the threaded portion being mounted in the stool, a hollow 95 horizontal arm located between the stool and the platform and provided at its upper end with a sleeve arranged on the smooth portion of the screw, a horizontally adjustable rod telescoping into the hollow arm and 100 provided at its outer end with a vertical sleeve, a graduated vertical rod adjustably mounted in the vertical sleeve, a horizontal marking device located above the platform and having a collar adjustably mounted on 105 the upper portion of the graduated rod, and means mounted on the hollow arm and the vertical sleeve for clamping the horizontal rod and the graduated vertical rod in their adjustment.

110 In testimony whereof I have hereunto set my hand.

MRS. HATTIE LOUISE HIBBS.
